FOREIGN PATENT DOCUMENTS

WO DM213517 12/2020

Primary Examiner — Cynthia R Underwood(74) *Attorney, Agent, or Firm* — McAndrews, Held & Malloy, Ltd.(57) **CLAIM**

The ornamental design for a trailer frame bracket, as shown and described.

DESCRIPTION

FIG. 1 is a top and front perspective view of a trailer frame bracket showing my new design;
 FIG. 2 is a front elevation view thereof;
 FIG. 3 is a rear elevation thereof;
 FIG. 4 is a right side elevation view thereof;
 FIG. 5 is a left side elevation view thereof;
 FIG. 6 is a top plan view thereof;
 FIG. 7 is a bottom plan view thereof; and,
 FIG. 8 is a bottom and rear perspective view thereof.
 The dashed broken lines in the figures illustrate portions of the trailer frame bracket that form no part of the claimed design.

1 Claim, 6 Drawing Sheets---
